CONNECTING MECHANISM FOR JACQUARD LEVERS

Application filed August 27, 1929. Serial No. 388,842.

This invention relates to improvements in driving mechanism for jacquards and it is the principal object of the invention to provide an improved form of joint between the 5 jacquard lever and the upright driving rod of a Jacquard loom.

In Jacquard looms there is a comparatively large lever located above the loom and forming part of the jacquard mechanism, this 10 lever moving about a horizontal axis which is substantially perpendicular to the crank shaft of the loom. A crank arm on the driving shaft rotating in a plane perpendicular to the axis of the shaft and substantially 15 parallel to the axis of the lever communicates driving power to said lever by means of a connector rod. Because of the fact that the arcs of movements of the lever and crank are in different planes it is necessary to provide 20 some form of universal joint which will not drop oil on the cloth or warp below the jacquard.

It is an important object of my present invention to provide a connection between a 25 jacquard lever and an operating rod one element of which comprises a pair of oil or paraffin saturated wooden blocks and the other element of which is a ball.

A still further object of my present invention relates to provision of means for holding the wooden blocks together under sufficient pressure to prevent lost motion but in such a way as to prevent compression of the 30 wood under the strain of holding devices 35 such as bolts.

Another object of my invention is the provision of a form of joint which may be used on either side of the jacquard lever when two 40 levers are present.

A further object of my invention is to provide the bearing blocks with holes somewhat larger than the holding bolts so that the blocks may adjust themselves to the ball.

With these and other objects in view which 45 will appear as the description proceeds, my invention resides in the combination and arrangement of parts hereinafter described and set forth in the claims.

In the accompanying drawings wherein a

convenient embodiment of my invention is set forth,

Fig. 1 is a front elevation of certain parts of a loom having my invention applied thereto, portions of the jacquard and driving shaft being set forth diagrammatically, 55

Figs. 2 and 3 are vertical sections on lines 2—2 and 3—3, respectively, of Fig. 1, on an enlarged scale,

Fig. 4 is a vertical section on line 4—4 of 60 Fig. 3,

Fig. 5 is a perspective view showing the relation between the wooden blocks and the lever for the jacquard,

Fig. 6 is a section on line 6—6 of Fig. 2, 65 and

Fig. 7 is a horizontal section on line 7—7 of Fig. 2.

Referring particularly to Figs. 1 and 5 I have shown a jacquard mechanism J which is operated by a lever 10 pivoted about a horizontal axis 11 which is substantially parallel to the warp threads. The top shaft 12 of the loom has secured thereto an arm 13 which may in effect be the hand wheel and said arm is pivotally connected as at 14 to an upright driving rod 15. The shaft 12 is given a complete revolution every pick of the loom so that the lever 10 is given a vertical reciprocation for every flight of the shuttle. 75 The parts thus far described are of common construction and operate in the usual manner. I do not wish to be limited, however, to a form of jacquard wherein the lever 10 is given a complete reciprocation for each 80 pick of the loom. 85

In carrying my present invention into effect I provide a ball holder 20 having a body 21 which slides along the lever 10 and is held in adjusted longitudinal position by means of set screws 22. Depending from the hub is an arm 23 through which extends the shank 24 of a ball member 25. The shank is threaded and is held in position on the arm by means of a check nut 26. A shoulder 27 90 on the ball member engages the left side of the arm as viewed in Fig. 3 to limit movement of the ball to the right.

The upright rod is provided with a socket element 30 the lower portion of which is 100

formed of a metallic plate 31 having a threaded boss 32 into which extends the driving rod 15. The upper part of the socket element is provided with a second plate 33 which has two threaded holes 34, one of which is clearly shown in Fig. 6. Bolts 35 extend through the bottom plate 31 and also upwardly through the block 33, being threaded into the holes 34 and held in fixed position by means of check nuts 36.

Located between plates 31 and 33 are two wooden bearing blocks or members 37 and 38 which are, respectively, above and below the ball 25. These blocks have aligning bores 39 and 40, respectively, through which extend the bolts 35. The bores 39 and 40 as shown in Fig. 6 are slightly larger in diameter than the bolts 35. The upper and lower bearing members are provided with substantially hemispherical cavities 41 and 42, respectively, and the upper bearing member has an abutting surface 43 which engages the upper surface 44 of the lower member 38.

In assembling the joint the bolts 35 will be inserted through the lower plate 31 and upwardly through the bores 40 of the lower bearing member 38. The ball 25 will then be inserted in the cavity 32 of the lower block, after which the upper bearing member 37 will be put in position, the bolts 35 being then extended upwardly through the bores 39 of said upper bearing member. The plate 33 is then placed on top of the upper bearing member and the bolts rotated by means of a wrench which engages the heads 45 thereof. In this way the bolts are threaded into the threaded holes 34 of the upper block. When sufficient pressure has been brought to bear on the ball by the upper and lower blocks the check nuts 36 will be set in position so that a further tightening of the blocks due to changes of the bolts 35 will not be possible.

It will be seen from Fig. 5 and also Figs. 2 and 3 that the ball joint occupies very little space measured in a horizontal direction. This feature is of consequence where a jacquard employs two or more levers 10. Upward movement of the driving rod 15 will move the socket member 30 upwardly to lift the ball 25, thereby rocking the lever 10 about its axis 11.

By reason of the fact that the bearing members 37 and 38 are formed of oil or paraffin impregnated wooden blocks it is unnecessary to apply any form of lubricant and for this reason the possibility of soiling the yarn or cloth is obviated.

If wearing should develop so that the socket becomes somewhat larger than the ball 25, the socket member may be taken apart and the surfaces 43 and 44 sandpapered or otherwise finished so that when reassembled the cavities 41 and 42 will have proper bearing relations with the ball 25.

From the foregoing it will be seen that I

have provided a simple and efficient form of connection between the driving rod and the jacquard lever so constructed that the use of oil or similar lubricant is unnecessary. It will further be seen that the check nuts 36 act to hold the predetermined setting of the bearing members 37 and 38 to prevent clamping and binding of the ball 25. Furthermore, when wearing develops on the part of the wooden members the surfaces 43 and 44 may be ground to take up any looseness which may have developed in the use of the joint. It will also be noted that by reason of the fact that the bores 39 and 40 are somewhat larger in diameter than the bolts 35 the wooden bearing members are able to adjust themselves to the ball 25. Again, by referring to Figs. 2, 3 and 5 it will be seen that the joint may be used on either side of the driven lever, due to the fact that the ball is held substantially centrally between the vertical outside faces of the wooden blocks and the cavity between said blocks is accessible from either of the outside faces.

Having thus described my invention it will be seen that changes and modifications may be made therein by those skilled in the art without departing from the spirit and scope of the invention and I do not wish to be limited to the details herein disclosed, but what I claim is:

1. In driving mechanism for a Jacquard loom having a driven lever element and a reciprocating driving rod element, a member secured in longitudinal adjusted position along one element, a ball secured thereto, and a socket member for the ball carried by the other element, said socket member comprising a pair of lubricant impregnated blocks, a pair of plates between which the blocks lie, and retaining means extending through both plates and blocks to draw the plates together and hold the blocks in position.

2. In driving mechanism for a Jacquard loom having a driven lever element and a reciprocating driving rod element, a member secured in longitudinal adjusted position along one element, a ball secured thereto, and a socket member for the ball carried by the other element, said socket member comprising a pair of spaced plates, a pair of recessed lubricant impregnated wooden blocks between the plates, and bolts extending through the plates and blocks to hold the latter in bearing relation with respect to the ball.

3. In driving mechanism for a Jacquard loom having a driven lever element and a reciprocating driving rod element, a member secured in longitudinal adjusted position along one element, a ball secured thereto, and a socket member for the ball carried by the other element, said socket member comprising a pair of spaced plates one of which has threaded holes therein, bolts extending

through both plates and threaded into the threaded holes, and lubricant impregnated bearing blocks located between the plates and having recesses to receive the ball, said bolts holding the blocks in bearing position with respect to the ball.

4. In driving mechanism for a Jacquard loom having a driven lever element and a reciprocating driving rod element, a member secured in longitudinal adjusted position along one element, a ball secured thereto, and a socket member for the ball carried by the other element, said socket member comprising a pair of spaced plates one of which has threaded holes therein, bolts extending through both plates and threaded into the threaded holes, lubricant impregnated bearing blocks located between the plates and having recesses to receive the ball, said bolts holding the blocks in bearing position with respect to the ball, and check means to prevent relative rotation of the bolts with respect to the plate having the threaded holes therein.

25 5. In driving mechanism for a Jacquard loom having a driven lever element and a reciprocating driving rod element, a member secured in longitudinal adjusted position along one element, a ball secured thereto, and a socket member for the ball carried by the other element, said socket member comprising a pair of spaced plates one of which has threaded holes therein, bolts extending through both plates and threaded into the threaded holes, and lubricant impregnated bearing blocks located between the plates and having recesses to receive the ball, said bolts holding the blocks in bearing position with respect to the ball, said bearing blocks having holes therein through which the bolts extend, the holes being of larger diameter than the diameter of the bolts.

In testimony whereof I have hereunto affixed my signature.

ELBRIDGE R. HOLMES.
